MOP

William Anthony Lamkey, Philadelphia, Pa.

Application November 23, 1932, Serial No. 643,999

7 Claims. (Cl. 15—229)

This invention relates to mops, and has for an object to provide a mop so constructed of such material that it will collapse upon a stick and retain itself upon the stick by such collapsing

5 process.

Another object of the invention is to provide a mop composed of material subject to shrinkage when wet, which said material is produced over a form maintaining a central opening for the insertion of a mop stick, and which collapses upon

10 said stick when the mop is wetted.

A further object of the invention is to provide a mop of some cordage, such for instance as cotton cordage, wound or built upon a central core 15 or mandrel, which will maintain the cordage with a central opening, then winding about the cordage other types of cordage subject to great shrinkage when wetted, and then replacing the central core by a mop stick which will be firmly 20 grasped by the collapsing mop structure, when wetted.

A further object of the invention is to provide a mop having a core formed therein and marketed therewith, which said core supports a cordage 25 body thereabout wound with other cordage in such manner that the core may be displaced by an entering mop stick, and the mop collapsed from the tension of the winding and shrinkage.

The invention therefore comprises a cordage 30 mop preferably formed about a central circular member and wound thereon by a cordage under considerable tension, and the core forced out of the mop by the introduction of the mop stick displacing said core, or as a modification the 35 solidifying of the mop structure by some impregnating soluble material which will maintain the central opening for the insertion of the stick until dissolved or softened by introduction into water.

In the drawing, 40 Figure 1 is a view of a mop of the present invention shown in side elevation, partly broken away, to show the stick in position and the fibers cut off.

Figure 2 is a view of the mop in end elevation, 45 Figure 3 is a diametrical sectional view through the mop showing the core in position, and the mop stick in position to displace the core.

Figure 4 is a similar diametrical sectional view 50 with the core displaced by the mop stick, and the mop collapsed upon the stick.

Figure 5 is a perspective view of the core, and 55 Figure 6 is a view in end elevation of the mop, which is constructed without a core by solidifying the cordage by a soluble material.

Like characters of reference indicate corresponding parts throughout the several views.

The mop, which forms the subject-matter of this application, is made in two types, one with and one without a core. With the type employing the core, a core 10 is employed. As shown in the drawing, this core 10 indicates a hollow core, such as may be made from rolled paper, but it is to be understood that any type of circular or cylindrical core is within the scope of the invention, such for instance as a plain cylindrical wooden core. With the core of the choice, cordage 11 is placed about this core, preferably by folding the ends, as at 12, which makes a neater appearing mop. With the cordage thus spaced as uniformly as may be about this core, the structure is wrapped by other cordage 13 under considerable tension to provide a tendency on the part of the cordage 11 to collapse, if the core is removed.

A mop stick 14 is employed preferably having a reduced neck 15. The head 16 approximates the diameter of the core. The stick 14, it will be understood, is of any material, and the term "stick" as employed, does not indicate any particular material. It is employed by forcing the core 10 out of the mop. The initial step is shown at Figure 3, with the head 16 of the stick abutting against the end of the core, which is being moved in the direction indicated by the arrow. Continued force, forces the core to the position shown at Figure 4 with the reduced part of the mop stick replacing the core, and by reason of the tension of the cordage 13, the cordage 11 will collapse onto the stick. When the mop is wetted, the shrinkage of the cordage 13 and the swelling of the cordage 11 will further bind the mop upon the stick.

Instead of forming the mop upon a removable core, as shown at 10, it may be formed upon a mandrel. In this case, the cordage is folded at 12', the same as shown at Figures 1 to 4 inclusive, but no bodily removable core is employed. When so formed upon the mandrel and wound by the cordage 13, that part of the structure is impregnated by some material, which is soluble in water and removable thereby. This may be of a gluey nature, which hardens in air and softens in water. The invention is no way limited to the particular material employed to impregnate the cordage. When so impregnated, it is allowed to remain upon the mandrel until it is hardened, then the mandrel is withdrawn, and the mop retains its form by reason of the rigidity imparted thereto by the impregnating material.

In this type, the stick is inserted into the mop and then immersed in water until the impregnating material has dissolved or softened to such an extent to allow the tension of the cordage 13 and the swelling of the other cordage to collapse the mop upon the stick when it will appear substantially as shown at Figure 4.

It will, therefore, be seen that it is wholly immaterial whether a core is employed and marked with the mop, as shown at Figures 1 to 4 inclusive, or whether it is formed in a rigid mass by soluble material. In any case, before the mop is ready for use, it collapses upon the mop stick and firmly holds itself in that position. To remove the mop from the mop stick to permit the stick to be re-used for another mop, it is merely necessary to cut the cordage 13, when the whole structure will fall apart and release the stick for re-use.

20 The various proportions shown in the drawings for the cordage, the core, and the stick are only illustrative and may be varied as experience may dictate.

The invention is hereby claimed as follows:—

25 1. A mop comprising a body composed of cordage extending longitudinally thereof and formed about a central member, other cordage under tension embracing said longitudinally extending cordage and over said central member, said embraced section being impregnated with soluble rigid material.

30 2. A mop head comprising a body of fibrous material having an opening therethrough, water shrinkable cordage wound about the fibrous material under tension tending to collapse the material to close the opening, and rigid soluble means impregnating some of said fibrous material and cordage and tending to restrain the collapsing.

3. A mop head comprising a body of fibrous material having an opening therethrough, cordage secured around the head at the opening under tension tending to collapse the material to close the opening, and soluble rigid means impregnating the fibrous material and tending to restrain the collapsing.

80

4. A mop head comprising a body of fibrous material having an opening therethrough, water shrinkable cordage secured around the head at the opening under tension tending to collapse the material to close the opening, and soluble rigid means impregnating the fibrous material and tending to restrain the collapsing.

85

5. A mop comprising a body composed of cordage about a central opening, other cordage wound under tension about and tending to collapse the first mentioned cordage to constrict the opening, and removable means engaging the cordage and substantially confined in extent to the region of said other cordage opposing the collapsing tendency.

90

6. A mop comprising a body composed of cordage about a central opening, other shrinkable cordage wound under tension about and tending to collapse the first mentioned cordage to constrict the opening, and removable means engaging the cordage and substantially confined in extent to the region of said other cordage for opposing the collapsing tendency.

105

7. A mop comprising a body composed of cordage about a central removable core, and other cordage wound under tension about and tending to collapse the first mentioned cordage to constrict the opening when the core is removed, said core substantially confined in extent to the region of said other cordage.
